COMBINED FRAME AND DOOR PANEL UNIT FOR A STORAGE LOCKER

Harold P. Lhotka and Thomas A. Joseph, North Canton,
and Earl P. Leiter, Youngstown, Ohio, assignors to
Republic Steel Corporation, Cleveland, Ohio

Filed Feb. 15, 1972, Ser. No. 226,649

Term of patent 14 years

Int. Cl. D25—02

U.S. Cl. D6—192

FIG. 1 is a front elevation of the combined frame and door panel unit for a storage locker embodying my new design.

FIG. 2 is a cross section taken on the line 2—2 of FIG. 1.

We claim:

The ornamental design for a combined frame and door panel unit for a storage locker, as shown.
